UNITED STATES PATENT OFFICE.

CHARLES G. ROGERS, OF PHILADELPHIA, PENNSYLVANIA.

DESIGN FOR AN AWNING-GUARD.

SPECIFICATION forming part of Design No. 28,106, dated December 28, 1897.

Application filed November 15, 1897. Serial No. 658,646. Term of patent 7 years.

To all whom it may concern:

Be it known that I, CHARLES G. ROGERS, a citizen of the United States, residing in the city and county of Philadelphia, State of Pennsylvania, have invented and produced a new and original Design for an Awning-Guard, of which the following is a specification, reference being had to the accompanying drawings, forming part thereof.

10 The leading feature of my design for an awning-guard is a hood with a depending chute.

Figure 1 represents a perspective view of an awning-guard embodying my design. Fig. 15 2 represents a section thereof on line x x , Fig. 1.

In the drawings, A designates a sheath

formed of the curved plate B, from the sides of which depend the flanges C D. On the flange C is the laterally-extending ear E. Depending from the sheath is the chute F, the outer wall G of which is continuous of the plate B, and the sides H J of which are continuous of the flanges C and D.

Having described my invention, what I claim as new, and desire to secure by Letters Patent, is—

The design for an awning-guard substantially as shown and described.

CHARLES G. ROGERS.
